C. B. FOWLER

TELEPHONE EXCHANGE SYSTEM

Filed Sept. 16, 1920

UNITED STATES PATENT OFFICE.

CLARENCE B. FOWLER, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed September 16, 1920. Serial No. 410,592.

To all whom it may concern:

Be it known that I, CLARENCE B. FOWLER, a citizen of the United States, residing in New York city, in the county of New York and State of New York, have invented 5 certain new and useful Improvements in Telephone-Exchange Systems, of which the following is a full, clear, concise, and exact description.

10 This invention relates to telephone exchange systems, and more particularly to such systems in which connections between telephone lines terminating at manual and automatic exchanges, are established by way of trunk circuits, over which automatic switches at the automatic exchange are actuated under the control of an impulse sender at the manual exchange to effect connections between subscribers of the manual exchange and subscribers of the automatic exchange.

15 The object of this invention is the production of an improved system of this nature wherein the work of the operator at the manual exchange is reduced to a minimum so that connections between subscribers of the manual and the automatic exchange may be established rapidly and efficiently.

20 One feature of the invention consists in the provision of means whereby the simple insertion of the calling plug of a cord circuit into the jack of a trunk circuit, places the impulse sender in operative relationship with the trunk circuit and causes the trunk circuit to be extended to an idle one of a plurality of trunks extending to the automatic exchange.

25 Another feature of the invention consists in the provision of a signal in a system of this character, to indicate to the operator at the manual exchange when the connection is in condition for the sending of impulses.

30 Still another feature of the invention consists in the provision of means, whereby, when the signal is actuated, indicating that the trunk, to which the calling plug of the cord circuit has been connected, is in condition for the sending of impulses and the 35 sender has been operated, it is impossible to disassociate the impulse sender from that

trunk until the impulse sender has delivered the impulses.

Another feature of the invention consists in the provision of means in a system of 55 this nature, wherein the simple insertion of the calling plug of the cord circuit into the jack of the trunk circuit not only serves to associate the impulse sender with the trunk circuit, and to extend the trunk circuit to an idle interoffice trunk, but also serves to disconnect the operator's telephone set from the cord circuit and to trip machine ringing which may be connected to the cord circuit. 60

65 For a more complete understanding of this invention reference may be had to the following description considered in connection with the accompanying drawing which illustrates one embodiment of the invention. 70

75 There is shown in the drawing, one of a plurality of trunk lines T which terminates at an operator's position at the manual exchange in a jack 21. Associated with the other end of the trunk circuit T is a non-numerical switch N, also located at the manual exchange. Accessible to the non-numerical switch N are a number of trunk lines leading to numerical or directly controlled switches, such as selector or 80 connector switches, at the automatic exchange. These switches being of a well-known type, it is not thought necessary to illustrate them in the drawing. The trunk circuit T is normally divided into inner 85 and outer sections, said sections being inductively united by means of condensers 28 and 29. Associated with the outer section of the trunk circuit T is a polarized relay 25, which controls a relay 26 associated with the inner section of the trunk which in turn controls the supervisory relay 11 of the cord circuit B. A slow-to-release relay 23 is energized a period sufficiently long after the plug 20 of the cord circuit B is 90 inserted into the jack 21 of the trunk circuit T, to cause the tripping of the machine ringing at the cord circuit B. 95

100 The manual station A may be of any suitable type of common battery station. At the manual exchange, the line of the station A is provided with a line jack 3, a

line relay 1, a cut-off relay 4 and a line lamp 2.

The operator's cord circuit B is adapted for use for either connecting two manual lines or for connecting a manual line with a trunk circuit such as T, extending to the automatic exchange. The cord circuit comprises answering and calling plugs 5 and 20 connected together through a repeating coil 10 and provided with supervisory relays 7 and 11. The cord circuit is also arranged for automatic connection and disconnection of the operator's telephone set and for automatic ringing.

15 The impulse sender S common to the trunk circuits, such as T, at the operator's position, is provided with interrupting contacts 61 and with off-normal contacts 60. Upon the initial movement of the sender S 20 from normal position, contacts 60 are closed and remain closed until the sender S returns to normal position. As the sender returns to normal position, contacts 61 are interrupted. For connecting the impulse sender S with the trunk line, there is provided for each operator's position, an automatic switching mechanism, which is shown above the dotted line in the drawing together with the impulse sender S. This switching mechanism 25 may be of any well-known type of step-by-step switch and the particular mechanism herein disclosed comprises three brushes 50, 51 and 52, which are adapted to be moved under control of the stepping magnet 45 over the contact banks D, E and F respectively. A pilot lamp 53 indicates to the operator when the impulse sender S is connected in operative relationship with a trunk circuit.

40 The nature of the invention is such that it is believed a clear understanding thereof will be obtained from a description of the operation of the system shown in the drawing.

45 Let it be assumed that station A originates a call, lighting the line signal 2 in the usual manner in response to the operation of the line relay 1. The operator in answering the call, inserts plug 5 of the cord circuit B 50 into jack 3 thereby disconnecting the line relay 1 and extinguishing the line signal 2 due to the operation of cut-off relay 4 of the line circuit which operates in series with relay 6 of the cord circuit over a path 55 extending from ground, winding of relay 4, sleeves of jack 3 and plug 5, left and middle windings of relay 6 in series, left-hand normal contacts of relay 9, resistance 12, front contact and armature of supervisory relay 7, 60 which is operated when plug 5 is inserted into jack 3, to grounded battery. Supervisory relay 7 is operated when plug 5 is inserted into jack 3 over a path extending from ground, upper left-hand winding of repeating coil 10, tips of plug 5 and jack 3 through

the loop of station A, rings of jack 3 and plug 5, winding of supervisory relay 7 and lower left-hand winding of repeating coil 10 to grounded battery. Due to the energization of supervisory relay 7 supervisory lamp 8 is prevented from lighting. Relay 6 in operating connects the operator's telephone set (not shown) to the cord circuit B and the operator may inquire the wants of the calling subscriber. Assuming that the calling subscriber desires connection with a line at the automatic exchange, the operator inserts calling plug 20 of the cord circuit B into jack 21 of the trunk circuit T, whereupon slow-to-release relay 24 of the trunk circuit T is energized over a path extending from ground winding of relay 24, inner right-hand armature and back contact of relay 22, rings of jack 21 and plug 20, lower normal contacts of relay 18, winding of supervisory relay 11, and lower right-hand winding of repeating coil 10 to grounded battery. Starting the operation of relays in the trunk circuit from the ring side is done in order to prevent a possibility of a false impulse being sent to the switch at the automatic exchange due to making and breaking the sleeve circuit while inserting the plug 20 into the jack 21. Relay 24 in attracting its left-hand armature removes ground from terminal 70 of the contact bank E. Relay 24 in operating also completes a circuit for relay 23 and motor magnet 45 over a path extending from grounded battery front contact and outer right-hand armature of relay 24 and thence in parallel, one path extending through the winding of relay 23 and back contact and left-hand armature of relay 22 to ground and the other through the right-hand armature and back contact of relay 27, right-hand armature and back contact of relay 43, resistances 75, winding armature and back contact of magnet 45 and brush 51 to ground. All the terminals of the bank E, to which no trunks are connected are strapped to ground. Relay 23 thereupon operates and completes a circuit for relay 9 of the cord circuit B and relay 22 of the trunk circuit T over a path extending from ground, front contact and left-hand armature of relay 23, winding of relay 22, sleeves of jack 21 and plug 20, winding of relay 9 and lamp 14 to grounded battery.

Supervisory lamp 14 thereupon lights, indicating to the operator that the connection is progressing. Relay 9 operates and at its left-hand contacts disconnects the left-hand and middle windings of relay 6 from series aiding relationship and connects the left-hand and right-hand windings in series opposing relationship thereby causing the de-energization of said relay 6 resulting in the disconnection of the operator's telephone set from the cord circuit B. Relay 9 in operating, also completes a circuit for relay 18 over

a path extending from ground, right-hand armature and front contact of relay 9, armature and back contact of relay 15, back contact and armature of relay 17, and winding of relay 18 to grounded battery. It will be noted, that the parallel path for current through the winding of relay 17 to relay 18, is short-circuited by the direct path through the armature and back contact of relay 15 thus preventing relay 17 from energizing at this time. Relay 18 in operating connects ringing current from a source 16 through the winding of relay 15 to the cord circuit at the alternate contacts of relay 18. This ringing current is immediately tripped, however, due to battery being connected to the ring of the cord circuit, when slow-to-release relay 23 of the trunk circuit T, operated over a path extending from grounded battery, outer right-hand armature and front contact of relay 23, rings of jack 21 and plug 20, lower alternate contacts of relay 18 and winding of relay 15 to source of ringing current 16. Relay 15 is thereupon energized and in attracting its armature removes the short circuit from relay 17 thereby connecting said relay 17 in series with relay 18. Relay 17 is thereupon energized and locks up under control of relay 9. Relay 18 is thereby short-circuited and retracts its armatures thus disconnecting the ringing current and rendering the talking conductors of the cord circuit B continuous. It is thus seen that ringing current is immediately automatically tripped when the plug 20 is inserted into the jack 21.

When relay 22 of the trunk circuit T energizes, a locking circuit therefor is closed through its front contacts and left-hand armature to ground. Relay 22 in operating opens the circuit for relay 23 causing the deenergization of this relay. Relay 23 being of the slow-to-release type maintains battery upon the ring of the trunk circuit T sufficiently long to cause the tripping of the ringing current. It will be noted that when relay 23 energized it also connected ground to the tip conductor 78 of the trunk circuit T, said ground being utilized for tripping machine ringing when party line ringing is employed, at cord circuit B. Relay 22 in operating also opens the original energizing circuit for slow-to-release relay 24, but immediately closes a local locking circuit therefor through the front contact and inner right-hand armature of relay 22.

As before stated, when relay 24 operated, a circuit for stepping magnet 45 was completed, under control of which, the brushes 50, 51 and 52 are stepped until brush 51 engages terminal 70, from which ground was removed when relay 24 energized, when said brushes come to rest. Relay 27 then operates over a path extending from ground, left-hand armature and back contact of re-

lay 43, back contact and armature of relay 44, pilot lamp 53, brush 52, terminal 71, armature and back contact of relay 26, right-hand winding of relay 27, and outer right-hand armature and front contact of relay 24 to grounded battery. Due to the resistance of the right-hand winding of relay 27, lamp 53 does not obtain sufficient current to light in this circuit. Relay 27, in operating, locks up over a path extending from grounded battery, front contact and outer right-hand armature of relay 24, left-hand winding of relay 27, left-hand armature and front contact of relay 27 and front contact and left-hand armature of relay 24 to ground. Relay 27 in operating disconnects battery from stepping magnet 45 and then connects ground through the left-hand contacts of relays 24 and 27 to terminal 70, thus rendering said terminal busy to other switches while the connection exists. It will be noted that if the brush 51 had been resting on terminal 70, when plug 20 was inserted into jack 21, ground would have been removed from terminal 70 as soon as relay 24 operated so that the stepping magnet would have not operated. Terminal 70 would have been rendered busy as soon as relay 27 operated.

At the same time that the brushes 50, 51 and 52 were being moved to associate the impulse sender S with the trunk circuit T, brushes 40, 41 and 42 of the switch N were being moved to extend the trunk T to an idle succeeding switch. Assuming that, when plug 20 is inserted into jack 21, brush 42, of the switch N is resting on a busy or grounded terminal 95, this ground causes energization of stepping magnet 32 of the switch N over a path extending from grounded battery, winding, armature and back contact of magnet 32, front contact and outer right-hand armature of relay 22, lower inner normal contacts of relay 31, and brush 42 to grounded terminal 95. Magnet 32 thereupon attracts its armature and moves the brushes 40, 41 and 42 and switch N in a manner well-known. Relay 31 does not operate at this time due to the direct path to ground at the terminal 95 of the switch N for battery through the winding of magnet 32. Under the control of stepping magnet 32, the brushes 40, 41 and 42 of the switch N are moved step-by-step until the ungrounded terminal of an idle succeeding switch is reached, whereupon relay 31 operates over a path extending from grounded battery, winding, armature and back contact of magnet 32, front contact and outer right-hand armature of relay 22 and winding of relay 31 to ground. Due to the high resistance of the winding of relay 31, magnet 32 will not operate in series therewith. Relay 31 in operating connects ground through its lower inner alternate contacts to the selected terminal to render

such terminal busy and extends the talking conductors of the calling line through to the succeeding switch through its upper and lower intermediate contacts. As soon as relay 31 operates, pilot lamp 53 lights, indicating to the operator that the circuit is in condition for dialing, over a path extending from ground, left-hand armature and back contact of relay 43, back contact and armature of relay 44, lamp 53, brush 52, terminal 71, armature and front contact of relay 26, lowermost armature and front contact of relay 31, front contact and right-hand armature of relay 27, and outer right-hand armature and front contact of relay 24 to grounded battery.

Upon receiving this signal the operator may actuate the impulse sender S in accordance with the number desired by the calling subscriber. Upon the initial movement of the sender S, off-normal contacts 60 are closed thereby operating relays 43 and 30 over a path extending from ground through contacts 60 of sender S, winding of relay 45, brush 50, terminal 72, winding of relay 30 and outer right-hand armature and front contact of relay 24 to grounded battery. Relay 43 in attracting its left-hand armature removes the short-circuit around relay 44, causing the operation of said relay 44. Relay 44 in operating removes the direct path to ground through pilot lamp 53 and causes said lamp to be extinguished due to the high-resistance of the winding of relay 44. Relay 43 in operating also opens the operating circuit of stepping magnet 45 so as to prevent its operation until the dial restores to normal position. This is done to prevent premature stepping of the position switch should the operator plug into another jack after the movement of the dial and before the dial is restored to normal. It is thus impossible to associate the sender with a second trunk circuit should the operator plug into a second trunk before the sender has delivered all the impulses.

Relay 30 in operating opens the talking conductors of the trunk circuit T and connects the interrupting contacts 61 of the sender S thereto. As the impulse sender S returns to normal position, the contacts 61 are intermittently opened in accordance with the digits dialed by the operator to cause the setting of switches at the automatic exchange in a manner well-known in the art.

When impulse sender S returns to normal position, relay 30 releases thereby rendering the talking conductors of the trunk circuit continuous, disconnecting the impulse sender S from the talking conductors and substituting therefor the bridge of the polarized relay 25. The sender S is then free for use with another trunk circuit. The polarized relay does not operate at this time since the direction of flow of current through its

winding is not in the proper direction to cause its operation. After the selecting impulses have been transmitted, the station of the called line may be signalled in a manner well-known in the art.

When the called subscriber responds, a current reversing relay may be energized at the automatic exchange.

The energizing of this relay may reverse the battery connections with the talking conductors of the trunk circuit whereby polarized relay 25 bridged across the talking conductors of the trunk circuit T, is energized and closes its contacts. Relay 25 in energizing bridges relay 26 across the inner section of the trunk circuit T over a path extending from tip conductor 78 through the winding of relay 26, front contact and armature of relay 25 to ring conductor 79. Due to the bridge across the inner section of the trunk circuit T, supervisory relay 11 of the calling end of the cord circuit will be energized thereby causing the extinguishing of supervisory relay 14, which indicates to the operator that the called subscriber has responded.

At the conclusion of conversation the subscribers restore their receivers to the switchhooks. The restoration of the receiver to the switchhook at the station A causes the deenergization of relay 7 and the lighting of answering supervisory lamp 8 which indicates to the operator that the calling subscriber has restored the receiver to the switchhook. When the called subscriber restores the receiver to the switchhook the battery connections to the trunk circuit T will be reversed again thereby causing the release of polarized relay 25. Relay 26 is thereupon removed from bridged relation with the talking conductors of the inner section of the trunk circuit T and supervisory relay 11 deenergizes permitting the lighting of the supervisory lamp 14 which indicates to the operator that the called subscriber has restored the receiver to the switchhook. The operator may thereupon disconnect the plug 5 from the jack 3 and the plug 20 from the jack 21, whereupon all apparatus associated with the cord and trunk circuits except the brushes 50, 51 and 52 will be restored to normal position. When the loop across the outer section of the trunk circuit T is interrupted the switches at the automatic exchange will be restored to normal in the well-known manner.

What is claimed is:

1. In a telephone exchange system, a calling line, a cord circuit, an operator's telephone set, means for automatically connecting said set with said cord circuit when said cord circuit is connected to said calling line, a plurality of trunk circuits, a non-numerical switch for each of said trunk circuits, numerical switches accessible to each of said

non-numerical switches, an impulse sender normally in inoperative relationship with said trunk circuits, and means responsive to the connection of said cord circuit with one 5 of said trunk circuits for disconnecting said operator's telephone set from said cord circuit, placing said impulse sender in operative relationship with the engaged trunk circuit and for operating said non-numerical 10 switch to extend the calling line to an idle numerical switch.

2. In a telephone system, a plurality of trunk lines each terminating in a jack, an impulse sender, a cord circuit terminating 15 in an answering and a calling plug, a step-by-step switch for placing said impulse sender in position to be connected with any one of said trunk lines, means responsive to the insertion of the calling plug of the cord 20 circuit into the jack of one of the trunk lines for operating said switch, and means operative when the switch is set and the sender is actuated for connecting it directly to the selected trunk line.

25 3. In a telephone system, a plurality of trunk lines, a non-numerical switch for each trunk line, an impulse sender common to said trunk lines, a cord circuit, and means responsive to the connection of said cord circuit with an idle trunk line and to the actuation of the sender for placing said sender in exclusive operative relationship with said trunk line and for causing said non-numerical switch to operate to extend said trunk.

35 4. In a telephone system, a plurality of trunk circuits, an automatic switch common to said trunk circuits, an impulse sender, a cord circuit, means responsive to the connection of said cord circuit with one of said 40 trunk circuits for causing said switch to operate to place said sender in connective relationship with said trunk circuit and means effective when the sender is actuated for connecting it directly to the seized trunk circuit.

45 5. In a telephone system, a plurality of trunk lines terminating in jacks, a step-by-step device, an impulse sender, a cord circuit terminating in an answering and calling 50 plug, means actuated when the calling plug of said cord circuit is inserted into the jack of one of said trunk lines for operating said step-by-step device to place said sender in connective relationship with said trunk line and means effective through said step-by-step device when the impulse sender is actuated for connecting the sender directly to the selected trunk line.

60 6. In a telephone system, a plurality of trunk lines terminating in jacks, a step-by-step device, a cord circuit terminating in an answering and calling plug, an impulse sender, a signal, means actuated, when the calling plug of said cord circuit is inserted 65 into the jack of one of said trunk lines, for

operating said step-by-step device to place said sender in connective relationship with said trunk line, means effective through said step-by-step device when the impulse sender is actuated for connecting it directly to the 70 selected trunk line, and means to actuate and maintain said signal actuated until the impulse sender has been operated.

7. In a telephone system, a plurality of trunk circuits each terminating in a jack, an impulse sender, a cord circuit terminating in an answering and calling plug and equipped with machine ringing, and means operated, when the calling plug of the cord circuit is inserted into the jack of one of the trunk 80 circuits, for tripping the machine ringing and for connecting the impulse sender with the trunk circuit.

8. In a telephone system, a calling line, a cord circuit terminating in an answering 85 and calling plug, a trunk circuit terminating in a jack, an impulse sender, an operator's telephone set, a source of machine ringing associated with said cord circuit, means responsive to the connection of the answering 90 plug of the cord circuit with the calling line for connecting the operator's telephone set in operative relationship with the calling line, and means responsive to the connection of the calling plug of the cord circuit with 95 the jack of the trunk circuit for disconnecting said operator's telephone set from the cord circuit, for tripping said machine ringing, and for placing the impulse sender in operative relationship with said trunk circuit. 100

9. In a telephone system, a plurality of trunk circuits, numerical switches accessible to each of said trunk circuits, a cord circuit, an impulse sender common to said trunk circuits, a pair of step-by-step switches, and means responsive to the connection of said cord circuit with one of said trunk circuits for operating one of said step-by-step switches to connect the impulse sender with 105 the trunk circuit and for operating the other of said switches to extend the trunk circuit to an idle numerical switch.

10. In a telephone system, an operator's position, a plurality of trunk lines terminating thereat, a non-numerical switch for each of said trunk lines, an impulse sender common to and normally disconnected from said trunk lines, cord circuits at said operator's position, and means responsive to the connection of one of the cord circuits with one of the trunk lines and to the actuation of the sender for placing the impulse sender in exclusive operative relationship with the engaged trunk line and for operating the 115 non-numerical switch individual thereto.

11. In a telephone system, a plurality of cord circuits, a plurality of trunk circuits, an impulse sender common to said trunk circuits, a step-by-step device actuated when 120 125 130

- one of said cord circuits is connected to one of said trunk circuits for associating the sender with the connected trunk circuit, means effective through said step-by-step device when the sender is actuated for connecting it directly to the seized trunk circuit and means for preventing the association of the sender with a second trunk circuit during the operation of said sender.
12. In a telephone system, a plurality of cord circuits, a plurality of trunk circuits, an impulse sender common to said trunk circuits, a step-by-step mechanism actuated when one of said cord circuits is connected to one of said trunk circuits for rendering the sender individual to the trunk circuit taken for use, means effective when the sender is actuated for connecting it directly to the seized trunk circuit and means for excluding the sender for use with other trunk circuits until the sender has operated to deliver the impulses.
13. In a telephone system, a plurality of trunk circuits, a plurality of switches one for each of said trunk circuits, an impulse sender, an automatic switch common to said trunk circuits, a cord circuit, and means responsive to the connection of the cord circuit with one of the trunk circuits for operating the switch common to the trunk cir-

cuits for connecting the sender to the trunk circuit taken for use and for operating the switch individual to the trunk circuit to extend the trunk.

14. In a telephone system, a plurality of cord circuits, a plurality of trunk circuits, an impulse sender common to said trunk circuits, an automatic switch actuated when one of said cord circuits is connected to one of said trunk circuits for rendering the sender individual to the trunk circuit taken for use, and means for connecting the sender directly to the selected trunk circuit when the sender is actuated and for excluding it for use with other trunk circuits until the sender has delivered the impulses corresponding to the setting of the sender.

15. In a telephone system, a trunk circuit, an impulse sender, a link circuit equipped for machine ringing, and means responsive to the connection of the link circuit with the trunk circuit for tripping the machine ringing and for placing the impulse sender in operative relationship with the trunk circuit.

In witness whereof, I hereunto subscribe my name this 13th day of September A. D., 1920.

CLARENCE B. FOWLER.
